(57) **CLAIM**

The ornamental design for a peeler for fruits and vegetables,
as shown and described.

DESCRIPTION

FIG. 1 is a front elevational view of a peeler for fruits and vegetables, shown with a storage apparatus attached.

FIG. 2 is a rear elevational view thereof.

FIG. 3 is a right side elevational view thereof.

FIG. 4 is a left side elevational view thereof.

FIG. 5 is a top plan view thereof.

FIG. 6 is a bottom plan view thereof.

FIG. 7 is a front and right side perspective view thereof.

FIG. 8 is a front elevational view showing a condition of use
with the storage apparatus removed.

FIG. 9 is a right side elevational reference view showing the
use position thereof.

FIG. 10 is a left side elevational reference view showing the
use position thereof.

FIG. 11 is a top plan reference view showing the use position
thereof.

FIG. 12 is a bottom plan reference view showing the use
position thereof.

FIG. 13 is a perspective reference view showing the use
position thereof; and,

FIG. 14 is a perspective reference view showing it in the
environment in which it is used.

The broken lines in the figures are for environmental pur-
pose only and form no part of the claimed design.
